(57) **CLAIM**

The ornamental design for a tailgate hinge, as shown and described.

DESCRIPTION

FIG. 1 is a front perspective view of a tailgate hinge according to my new design;

FIG. 2 is a rear perspective view of the tailgate hinge of FIG. 1;

FIG. 3 is a front elevation view of the tailgate hinge of FIG. 1; FIG. 4 is a top elevation view of the tailgate hinge of FIG. 1; FIG. 5 is a bottom elevation view of the tailgate hinge of FIG. 1;

FIG. 6 is a left elevation view of the tailgate hinge of FIG. 1; and,

FIG. 7 is a right elevation view of the tailgate hinge of FIG. 1. The broken lines environment is for illustrative purpose only and forms no part of the claimed design.
